United States Patent Office

Des. 222,783
Patented Dec. 28, 1971

222,783

LAWN COMBINE

Donald W. Burton, Gates, N.Y., assignor to
Lawn Medic, Inc., Rochester, N.Y.

Filed Apr. 8, 1970, Ser. No. 22,327

Term of patent 14 years

Int. Cl. D15—03

U.S. Cl. D40—1

FIG. 1

FIG. 2

FIG. 3

FIG. 4

FIG. 5

FIG. 1 is a side elevational view of a lawn combine embodying my new design;

FIG. 2 is a bottom plan view thereof;

FIG. 3 is a top plan view thereof;

FIG. 4 is a front elevational view thereof; and

FIG. 5 is a rear elevational view thereof.

I claim:

The ornamental design for a lawn combine, substantially as shown.
